WATER PUMP BAFFLE

Arthur Marr, 589 Wesley Ave.,
Oakland, Calif. 94606

Filed Nov. 10, 1971, Ser. No. 197,634

Term of patent 14 years

Int. Cl. D15—02

U.S. Cl. D65—1 R

FIG. 1 is a front elevation of water pump baffle embracing my new and ornamental design;
FIG. 2 is a bottom plan view looking up at the article;
FIG. 3 is a top plan view, looking down on the article;
FIG. 4 is one side elevation of the article;
FIG. 5 is the opposite side elevation of the article;
FIG. 6 is a back elevation of the article; and
FIG. 7 is a fragmentary section taken along line 7—7 as indicated at FIG. 1.

I claim:

The ornamental design for a water pump baffle, as shown.
